UNITED STATES PATENT OFFICE.

MAX GREENBERG, OF CLEVELAND, OHIO, ASSIGNOR OF ONE-HALF TO HERMAN S. KANTON AND ONE-HALF TO SADIE GREENBERG, BOTH OF CLEVELAND, OHIO.

STAND BOILER.

Application filed November 8, 1922. Serial No. 599,671.

To all whom it may concern:

Be it known that I, MAX GREENBERG, citizen of the United States, residing at Cleveland, in the county of Cuyahoga and 5 State of Ohio, have invented certain new and useful Improvements in Stand Boilers, of which the following is a specification.

This invention relates to stand boilers, and in some respects is an improvement on 10 the boiler or water heater shown in my United States Patent #1,980,838 issued April 13, 1909.

The boiler is of that type provided with a central fire tube or flue, within a surrounding water space, a coil of water pipes extending through the flue and in the space below the same above the burner, this pipe being connected at one end to the main water chamber of the boiler and at the other end 20 to the outlet, said outlet being also connected to the water space in the boiler shell.

The object of the present invention is to provide such a boiler with certain improvements of construction, as will be more fully 25 apparent from the following description, one feature of the improvement relating to the circulation connections and another to a thermostatic connection.

In the accompanying drawings Fig. 1 is 30 a vertical section of the structure. Fig. 2 is a section on the line 2—2 of Fig. 1; and Fig. 3 is a section on the line 3—3 of Fig. 1.

The boiler includes a tank or cylinder 6, with a cap 6^a and a base 6^b, and within this 35 cylinder a large water chamber is formed by means of a central fire tube 11 with conical ends 11^a and 11^b connecting the bottom and top thereof with the wall of the cylinder 6.

40 The cold water inlet is indicated at 7, the inlet pipe extending as indicated at 7^a down into the lower part of the tank. The outlet pipe 8 connects to a header 10^b located in the upper part of the cylinder. This header 45 has a connection at 8^a projecting downwardly into the tank. The header is also connected to the upper ends of the tubes 10 and 10^a which form the continuation of the two coils 9 and 9^a, the latter being located 50 in the conical space under the tank, above the burner 15, and the pipes 10 and 10^a extending through or within the tube 11. The header 10^b also has a connection at 10^c with the top of the tank. 16 indicates a drain 55 cock from the bottom of the tank.

A thermostatic tube 14 encloses a thermostat which, by means not shown, controls the supply of gas to the burner 15. This tube 14 is connected at its upper end to the tank through the outer wall of the latter, and at its lower end is connected to a tube 13 which has an opening 13^a located directly below the lower end of the cold water inlet pipe 7^a.

60 Mounted within the lower part of the tank is a shell or shield 12 which is conical in shape and is spaced slightly from the conical end bottom piece 11^a of the tank. It is found that this shell will prevent sweating of the outside of the tank in cold weather, as it 65 serves to direct the heated water in the tank upwardly around the tube 11, and the cooler water circulating down the outside of the tank will have less tendency to produce condensation on the outside of the tank.

70 The cover 6^a at the top encloses the upper part of the boiler and serves to conduct the products of combustion to any suitable stack or outlet.

75 In operation, there is a circulation through 80 the pipes 10 and 10^a and the coils, and also from the tank upwardly through the connection 10^c to the header and downwardly through the pipe 8^a, and this water mixes with the water circulating through the coils. 85 When a faucet is opened, the water is drawn through the pipe 10^c from the hottest part of the tank, and also to some extent through the pipe 8^a, and this tempers the water in the manifold 10^b. The heated water is therefore drawn from various parts of the device 90 and the boiler is re-supplied with water through the inlet pipe 7^a.

95 Ordinarily there is a circulation of water through the thermostat pipe 14 which decreases the supply of gas as the heat of the water increases. However, when water is drawn from the tank, the cold water discharges from the lower end of the pipe 7^a and is injected through the hole 13^a into the connection 13 and the pipe 14, thereby 100 cooling the thermostat and providing a great supply of gas to the burner accordingly, so that as water is drawn the burner combustion will be increased, thereby providing an automatic control of the fuel and heat supply.

105 The invention is not limited to the details shown and described, but modifications may be made in various ways within the scope 110 of the following claim.

I claim:

A stand boiler having a tank with a central flue, provided with conical sections at the top and bottom, a transverse header in the upper conical section of the flue, a water heating pipe connected at opposite ends to the header and to the tank, and extending downwardly thru the flue and formed into a coil in the lower conical section, a burner under the coil, a connection between the header and the top of the tank, and another

connection between the header and the tank, the latter connection extending downwardly into the tank below the first mentioned connection, said connections being independent 15 of the water heating pipe.

In testimony whereof, I affix my signature in presence of two witnesses.

MAX GREENBERG.
